UNITED STATES PATENT OFFICE.

ERNST LINDNER, OF NEW YORK, N. Y.

DESIGN FOR A BURNER-FIXTURE.

SPECIFICATION forming part of Design No. 26,617, dated February 9, 1897.

Application filed December 23, 1896. Serial No. 616,693. Term of patent 14 years.

To all whom it may concern:

Be it known that I, ERNST LINDNER, residing in the city, county, and State of New York, have invented and produced a new and original Design for a Burner-Fixture, of which the following is a specification.

The leading feature of my design is a burner-fixture substantially as shown.

The accompanying drawing exhibits a burner-fixture embodying my design.

In the drawing, *a* is a tubular column, whose base *a* is surrounded by a reticulated base

ornament *b*, surmounted by a projecting ledge *c* and foliated ornaments *d*. Rising from the base are columns or standards *e*, joined by a band *f*, from which project ornamental pieces *g*.

What I claim is—

The design for a burner-fixture, substantially as shown.

ERNST LINDNER.
